UNITED STATES PATENT OFFICE.

ELLSWORTH B. A. ZWOYER, OF READING, PENNSYLVANIA.

DESIGN FOR FUEL.

SPECIFICATION forming part of Design No. 27,484, dated August 3, 1897.

Application filed May 5, 1897. Serial No. 635,262. Term of patent 14 years.

To all whom it may concern:

Be it known that I, ELLSWORTH B. A. ZWOYER, a citizen of the United States, and a resident of the city of Reading, in the county of Berks and State of Pennsylvania, have invented and produced a new and original Design for Lumps or Pieces of Fuel, of which the following is a specification, reference being had to the accompanying drawings, which form part of this specification, and in which—

Figure 1 is a plan view of a lump of fuel of my design; Fig. 2, an elevation of one side of my lump of fuel, and Fig. 3 an elevation of the lump of fuel at right angles to the elevation shown in Fig. 2.

In plan my lump of fuel is square, with slightly-rounded corners A, as shown in Fig.

1. Its elevation upon one side is that of two truncated pyramids B B', placed base to base, furnished with rounded corners C and separated by a flat rectangular body D, the corners of which are also rounded, as shown in Fig. 2, and its elevation at right angles to the side shown in Fig. 2 is that shown in Fig. 3, the body D remaining the same, but the outlines of the sides being curved, as shown at E E'.

I claim as my invention—

The design for a lump of fuel as herein set forth.

ELLSWORTH B. A. ZWOYER.
